DRAFTING INSTRUMENT

Henry E. Walker, Burbank, Calif.

Application November 2, 1946, Serial No. 707,386

3 Claims. (Cl. 33—27)

1

This invention relates to splines, such as are used by mechanical draftsmen for laying down ship-lines, contours and lines on maps, railway curves, etc.

One of the objects of this invention is the provision of a spline and means associated therewith that will enable the draftsman to do more accurate work than heretofore, and to ink in the lines laid out or to be put down free from the likelihood of blotting through accidental running of the ink under or to the spline.

Another object of the invention is the provision of a spline and means associated therewith that will enable any draftsman, whether skilled or unskilled, to lay out and ink in a curve of practically any sort or a plurality of connected or unconnected curves, without difficulty and without the usual hazards of blotting or inaccuracies due to shadows along the spline.

A still further object of the invention is the provision of a spline and means associated therewith for performing any desired operation along a curve that is parallel with and spaced from said spline, such as cutting metal by a burning torch, or marking with pencil, pen, scratch awl or any other desired instrument.

The conventional splines may be a flexible strip of wood, hard rubber, steel, plastic or a combination of two or more of such materials or practically any material that is sufficiently flexible to be bowed to the desired degree that may be required without permanent distortion.

Rather heavy splines of plastic material are common, and in use, the strip of plastic is positioned on edge on the paper or surface bearing the points that define the curve. Weights are employed in some instances for holding the strip curved when bent so as to enable the draftsman to run a pen, pencil, or scribe along the edge that is in engagement with said surface. The strip is usually grooved longitudinally thereof on its upper edge, and the weights each have a pin projecting therefrom and into said groove.

It is not unusual for the draftsman to find that the curve marked on the surface is inaccurate due to the confusion caused at one or more points along the length of the spline by a shadow cast by the latter, or by wobbling of the pen or pencil, or by turning the pen so that its point makes a wider or narrower line than at other points and also in an attempt to follow the bottom edge of the spline so as to reduce the chance for inaccuracy it very frequently happens that the ink flows to and under the spline and along the latter, creating a blot.

With the present invention all the above objectionable occurrences are overcome.

Instead of a marker, such as a pen, pencil, scratch awl or the like, a burning torch can be substituted to enable the workman to cut along

2

the desired curved line instead of merely marking along such line, the spline and weights being made of the desired length and weight for the job to be done.

Other objects and advantages will appear in the description and in the drawings.

In the drawings,

Fig. 1 is a plan view of a spline and device thereon illustrative of the invention.

Fig. 2 is a side elevational view of the invention shown in Fig. 1.

Fig. 3 is a fragmentary plan view of a portion of the carriage on the spline, the pivot for supporting said portion being in section.

Fig. 4 is a fragmentary elevational view of the portion shown in Fig. 3 looking from the end of the carriage, said portion being removed from the spline.

Fig. 5 is a sectional view taken along line 5—5 of Fig. 3 but omitting the spline.

Fig. 6 is an enlarged, fragmentary view showing the outer end of a weight pin in engagement with the spline, the latter being shown in section, and said view being along line 6—6 of Fig. 1.

Fig. 7 is an enlarged cross sectional view taken along the line 7—7 of Fig. 1 showing the points where the carriage is supported on the upper edge of the spline.

Fig. 8 is an enlarged sectional view taken along line 8—8 of Fig. 4, but showing the spline in position.

Fig. 9 is a fragmentary bottom plan view showing a portion of the detent spring at the pen-holding part of the device.

Fig. 10 is a plan view showing the spline at a curve with the carriage on said spline.

Fig. 11 is a fragmentary elevational view showing a cutting torch on the device instead of a pencil or pen.

In detail, the invention comprises a spline 1 that is preferably of steel although it may be of any resilient material for some kind of work. Spring steel provides a highly flexible yet sufficiently rigid spline for doing many jobs where heavier plastic, wood, or hard rubber would be inoperative. The spring steel spline may be of any desired length, width and weight for the job to be done. This spline is adapted to be positioned on edge on a horizontal plane surface and in any desired curve on such surface.

Said spline is formed with a row of openings 2 extending longitudinally thereof, and which row is about a third of the distance between the top and bottom edges from the bottom edge.

The means for holding said spline on said surface in any desired curve comprises a plurality of weights 3. These weights may have felt base coverings so as not to injure the surface supporting them when slid over such surface. Each weight has a pin 4 projecting laterally from one

side thereof, and the outer end of each pin is formed with a downwardly opening taper-sided notch 5 in which the lower edge of each opening 2 is adapted to fit or to be received. Upon connecting a number of weights with the spline at the desired points the spline may be curved by shifting the weights so as to form the desired curve and the weights will then hold the spline in the desired curve or curves. Any number of weights may be used and the spline may be curved sinuously instead of a single curve.

Said spline may be of any length and any number of weights may be used.

Supported on said spline for movement longitudinally of the latter is a carriage, generally designated 6. This carriage is removable from the spline, as will appear later on and carries the marker that will make the desired line on the surface on which the spline is positioned.

Carriage 6 comprises an elongated carriage member 7 that is adapted to extend over the upper edge 8 of the spline longitudinally of the latter. This member 7 may be in the form of a flat, straight bar positioned with its flat sides horizontal, as shown in Figs. 1, 2.

A ball bearing is carried at each end of said member 7, said bearings being numbered 9, 10. The bearing 9 pivotally supports one end of a vertical pivot 11 that extends upwardly from a head element 12, said element depending from the lower side of member 7. The head element 12 is rotatable relative to member 7 about the vertical axis of said pivot 11.

The element 12 is formed with a vertical, downwardly opening slot 13 (Fig. 4) in its lower side and in which slot said spline is normally positioned. At the upper end of slot 13 is a roller 14 that engages the upper edge of the spline (Fig. 7). Roller 14 extends transversely across said upper edge and supports the element 12 for movement along said spline.

The portion 15 of element 12 that forms one side of slot 13 (Fig. 5) is hingedly secured to the main body of said element 12 by means of a link 16 that is pivoted at 17, 18 at its ends to said body and to portion 15 so that the latter may move toward and away from the opposite side of said slot. A leaf spring 19 secured to the main body of element 12 yieldably engages the portion 15 to urge it toward the opposite side of slot 13 at all times.

The said portion 15 carries two pairs of vertically aligned and vertically spaced balls 22, 23 in the side thereof that defines one side of slot 13 and these balls project into said slot, while the portion 21 of element 12 that forms the other side of slot 13 carries one pair of balls 20. The pair of balls 22, 23 are equally spaced from the pair of balls 20, and the upper balls of all pairs are in the same horizontal plane while the lower balls of all pairs are also in a common horizontal plane below the upper balls.

The spline 1 is held between the balls 20 at one side of slot 13 and the balls 22, 23 at the opposite side. By this means the element 12 cannot wobble on the spline (due to the upper and lower sets of balls) and the spline can bend in the slot without localized distortion. The movement permitted by the movable portion 15 will enable the balls 22, 23 to move toward and away from portion 21 as the degree of the curve varies.

Secured to the portion 21 of element 12, and rigid therewith is a vertical plate 25 (Figs. 1, 2). This plate extends along the member 7, at a level

5 below it, and is provided with a horizontal pivot 26 adjacent the end remote from said element 12. Pivotedly supported on this pivot 26 is an arm 27 that extends forwardly alongside plate 25 back toward the element 12, but on the side of plate 25 that is opposite said element.

10 The arm 27 is relatively wide at its outer end portion that is adjacent element 12 and extends to the upper edge of plate 25 adjacent said element where it carries a horizontal pivot 28 on which is supported a segment plate 29, at the radial point of the latter.

Extending radially of said pivot and secured to said segment plate is a tracing pin 30 that is adapted to slidably engage the surface on which the spline is supported when said segment is rotated on pivot 28 to bring said pin vertical and pointing downwardly.

20 Also extending radially of pivot 28 and secured to said segment plate is a well-type lettering pen 31, such as is employed for use with the ordinary "Leroy" or "Wrico" lettering sets. When the segment 29 is rotated so that the pen 31 is vertical and in substantial writing engagement with the surface 33 on which spline 1 is supported, it will be seen that said pen will mark the curve as the carriage is moved along the spline.

30 A spring 34 adjacent pivot 26 that connects arm 27 with plate 25 functions to yieldably urge the pen 31 or tracing pin 30 against said surface 33.

35 A detent spring 35 carried on arm 27 engages a depression in the segment 29 adjacent pen 31 or pin 30 according to which is vertical for releasably holding said segment in adjusted position.

40 The elongated carriage member 7 is provided at its end opposite the element 12 with a foot element 40 that is below said member and that is pivotally connected to said member by a pivot 41 that is in ball bearing 10. This foot element 40 (Fig. 7) is also formed with a downwardly opening slot 42 therein, in which the spline is received, and a roller or pin 43 in the upper end of said slot engages the upper edge of the spline. The slot 42 is just a plain slot in this instance and without balls such as were used in element 12.

50 From the foregoing it will be seen that the carriage 6 has a two point contact with the upper edge of the spline 1 at roller 14 and pin 43 and the element 12 cannot tilt to cause the vertically aligned balls 20, 22, or 23 to tilt out of their alignment perpendicular to spline 1. In other words, the carriage will always remain level and will not tilt in any direction relative to the spline.

60 The central axis of pivot 11 that carries the element 12 extends through the spline 1 and the arrangement of balls 20, 22, 23 is such that the pen 31 or pin 30, whichever is vertical and in working position, will be in a vertical plane that extends through the balls 20 and that bisects the space between the pairs of balls 22, 23, which plane is perpendicular to a plane extending through the pairs of balls 22, 23. Thus the 65 marker, whether pen or pencil, or the pin 30, whichever is in working position, will be on a line that is perpendicular to the tangent of that portion of the curve of spline 1 that is between the pairs of balls 22, 23 and the marker or pen will inevitably follow a path that is parallel with the spline.

70 In operation the draftsman first preferably

swings the segment plate 29 to bring the tracing pin into vertical operating position. He then adjusts the spline so that the pin will pass through the points plotted on the paper or surface 33. This is easily and quickly done by shifting the weights to move the spline to the desired curve. Then the segment is swung to bring the pen into operating position and the curve is quickly inked in by a single movement of the carriage along the spline. No blotting can possibly occur and the line is of exactly the same thickness from end to end.

In sheet metal shops, shipyards and other manufacturing plants, a burning torch 50 (Fig. 11) may be substituted for the pen, or any other desired implement may be so substituted. By this means the use of templates may be omitted as the spline provides means that enables the workman to follow any curve of practically any degree and kind.

In the claims, the use of the word "marker" is intended to include a torch, pencil, pen, scratch awl, cutter, welding rod, etc.

It is to be noted, as seen in Fig. 10, that the plate 25 will swing outwardly and away from the convex side of the curved spline when the carriage goes around a curve such as illustrated. In Fig. 2 it will be seen that the plate 25 is free to swing past the member 40 in the opposite direction or toward the spline when the marker is moved along the concave side of a curve made by the spline. Thus the device may be used for making a sinuous line as well as other curves, such as parabolas, hyperbolas or irregularly plotted curves.

It is to be understood that the detailed description and drawings are not to be considered restrictive to the invention, but merely illustrative of a preferred form.

I claim:

1. A drafting instrument comprising a spline adapted to be supported on edge on a plane, generally horizontally disposed surface and free for bending into any desired circular or non circular curve on said surface, a carriage element supported on the upper edge of said spline for movement longitudinally of the latter, a plurality of bearings on said carriage element including a horizontally spaced pair engaging one side of said spline at spaced points and one bearing engaging the opposite side of said spline at a point intermediate said pair, means for yieldably urging said bearings against said spline for holding the carriage on the spline free from play during movement of said carriage along said spline irrespective of the degree of curvature of said spline, and a marker on said carriage element spaced from one side of said spline, means securing said marker to said carriage element in a vertical plane extending through said one bearing and perpendicular to a plane bisecting the bearings of said pair, said marker being adapted to slidably engage said surface for marking on the latter, a head member pivotally secured at one end to said carriage element for movement of the former about a vertical axis relative to the latter, and means at the opposite end of said head member pivotally secured thereto for movement about a vertical axis and supported on the upper edge of said spline for movement along the latter together with said carriage element.

2. A drafting instrument comprising a spline adapted to be supported on edge on a plane, horizontal surface and free for bending into any desired circular or non circular curve on said sur-

face, a carriage element supported on the upper edge of said spline for movement longitudinally of the latter, a plurality of bearings on said carriage element including a horizontally spaced pair engaging one side of said spline at spaced points and one bearing engaging the opposite side of said spline intermediate said pair, each bearing of said pair comprising a pair of vertically spaced balls and said one bearing comprising a pair of vertically spaced balls, means yieldably urging said pair of bearings against said spline and urging said spline against the balls of said one bearing, a marker on said element spaced from one side of said spline and in slidable engagement with said surface, and means securing said marker to said carriage element in a vertical plane extending through said one bearing and perpendicular to a plane bisecting the elements of said pair.

3. A drafting instrument comprising a spline adapted to be supported on edge on a plane, horizontal surface and free for bending into any desired circular or non circular curve on said surface, an elongated carriage member adapted to extend longitudinally over the upper edge of said spline, a head element at one end of said carriage member pivotally secured thereto for swinging about a vertical axis and depending from said member, a foot element at the opposite end of said carriage pivotally secured thereto for swinging about a vertical axis and depending from said member, said head element and said foot element each being formed with a downwardly opening slot in which said spline is slidably received, a bearing in the closed upper end of each slot engaging the upper edge of said spline, a marker carried by said head element spaced from one side thereof and from said spline and adapted to engage said surface for marking on the latter, means securing said marker to said head element for swinging of the marker with said head element about the vertical axis of the pivot supporting the latter, and means for holding said marker at a point along a line perpendicular to the tangent of the curve of said spline at the point where said vertical axis of the pivot of said head member extends through said spline, said latter pivot being positioned to extend through said spline at all times during movement of said latter head along said spline.
